UNITED STATES PATENT OFFICE.

JOHN E. BELL, OF BROOKLYN, NEW YORK, AND EDWARD W. ISOM, OF WINNETKA, ILLINOIS.

PRESSURE STILL.

Application filed April 8, 1921. Serial No. 459,555.

To all whom it may concern:

Be it known that we, JOHN E. BELL and EDWARD W. ISOM, citizens of the United States, residing, respectively, at Brooklyn, 5 county of Kings, and State of New York, and Winnetka, county of Cook, and State of Illinois, have invented certain new and useful Improvements in Pressure Stills, of which the following is a specification.

10 The pressure stills to which our invention relates are designed to crack petroleum, gas oil and other heavy hydrocarbons and to convert them as far as possible into lighter hydrocarbons such as those constituting the 15 fraction known on the market as gasoline. In cracking such heavy hydrocarbons they are heated up to very high temperatures, commonly under high pressure, with the result that the heavier oils, or a portion thereof, are broken down forming lighter oils which are vaporized and driven off. The vapors are condensed and submitted to further treatment to form the commercial product. In the formation of the lighter oils 20 carbon is freed in considerable quantity remaining behind in the heavy oil and tar in the still and depositing on the heat transmitting surfaces of the latter with which the oil is in contact. The carbon and heavy tar 25 are very poor conductors of heat and when deposited upon the heating surfaces of the still which are exposed to the heating gases insulate the wall from the cooling effect of the oil so that the walls are apt to become 30 overheated, the temperature of the metal increasing over the temperature of the oil to an extent dependent upon the thickness of the carbon deposit and the amount of heat externally delivered to the heating surface 35 from the furnace. As a consequence unless the stills are frequently shut down for cleaning or the temperature of the furnace reduced below that which is most efficient, it is difficult to maintain the stills in operation for a sufficient length of time to make 40 such operation commercially practical. There is also considerable hazard to life and property because of the possible bursting of the overheated portions of the still, which is

increased because of the pressure usually 50 maintained in such stills which may be as much as one hundred pounds per square inch or more.

The surfaces of the still most exposed to the heat of the furnace are of course most 55 apt to suffer, and in the case of a tubular still, to which our invention more particularly relates, the tubes with which the products of combustion from the firebox first come into contact receive the greatest 60 amount of heat from the furnace and consequently suffer the most. It is one of the objects of our invention to provide an improved apparatus for cracking oil in which the heating tubes exposed to the products 65 of combustion from the firebox at the highest temperatures contain oil which is substantially free from carbon and tar, and in which the oil as it accumulates tar and carbon and loses its content of crackable hydrocarbons flows successively through heating tubes exposed to products of combustion from the furnace at successively lower temperatures, and affording greater total surface for deposition of carbonaceous material, 70 thus enabling the still to be operated for a greater length of time between cleanings 75 than is possible with the constructions heretofore known.

With this object in view we provide a 80 tank or drum containing the main body of oil to be cracked and connected as usual to a condenser in which the vapors constituting the desired fraction are condensed. The drum is provided with transverse partitions 85 of any desired number which separate the drum into a series of compartments, and the oil to be cracked is fed to the first compartment in the series and overflows from the first compartment to the second and from 90 the second to the third, and so on, being subjected to the cracking operation in each compartment so that it is, step by step, deprived of portions of the hydrocarbons 95 which yield to the cracking operation and increases step by step in the proportion of carbon and tar contained. The several compartments are provided with heating tubes

so connected thereto that the oil in each compartment circulates to the heating tubes which appertain thereto and back to the same compartment, the sets of heating tubes 5 being arranged successively in the flues of the furnace so that those appertaining to the compartment first receiving the oil are subjected to the highest temperature and succeeding sets of tubes are subjected to 10 progressively decreasing temperatures.

In order that the vapors of the desired composition may be developed approximately in equal quantities in the several compartments and the temperature of the oil 15 itself maintained, the number or total length of heating tubes is increased successively from the first to the last compartment. This arrangement also provides a large extent of surface on which carbon can be deposited 20 in the coolest part of the still where it is least likely to be baked to a hard crust.

The circulation through the heating tubes may be natural or forced. In a companion application 437,662, filed January 17, 1921, 25 we have described and claimed a construction such as outlined above in which the circulation of the oil is independent of any mechanical or other forcing means, being due to convective action caused by the heating 30 of the oil and the evolution of vapors and gases thereby.

In the construction of the present application, however, we employ a forced circulation, pumps being provided for the several compartments which receive the oil 35 therefrom and pump it through the respective sets of heating tubes and back to the compartments. Other features of novelty will appear from the drawing taken in connection with the following description. It 40 is to be understood, however, that the specific disclosure is for the purpose of exemplification only and that the scope of the invention is defined in the following claims 45 in which we have endeavored to distinguish it from the prior art so far as known to us, without, however, relinquishing or abandoning any portion or feature thereof.

In the drawing, Fig. 1 is a vertical longitudinal sectional view of a preferred form 50 of still embodying our invention, parts being shown in elevation; Fig. 2 is a vertical transverse section therethrough on line 2-2 of Fig. 1 looking in the direction of the 55 arrows; and Fig. 3 a plan partly in horizontal section on the line 3-3 of Fig. 1.

Each part is identified by the same reference character wherever it occurs in the several views.

60 In the preferred construction shown the drum 6 which contains the bulk of the still charge is of the cylindrical, boiler type and is supported on I-beams 7 upon the furnace structure 8. The drum is divided by partitions 9 into a number of approximately 65

equal chambers 10, 10^a, etc., the latter being here indicated as four in number. The oil to be cracked is first fed into the front compartment 10 from which, after it reaches the desired level, it overflows through pipe 11 70 into the second compartment and thence by overflow pipe 11^a into the third compartment and so on. The tar finally is drawn off from the last compartment. If desired the oil may be fed directly from a supply tank 75 to said first compartment through inlet B, or it may be introduced through the reflux tower C, a supply pipe D being provided for this purpose. E is the vapor line.

The furnace is provided with a fire-box 80 12, which may be of any usual or suitable character, and a series of vertical flues 13, 13^a, 13^b, 13^c, the first of which connects with the fire-box through the throat 14, the second with the first at the top of the furnace 85 structure through passage 15, the third with the second through passage 16 at the bottom of the furnace structure and the fourth with the third through passage 17 at the top of the furnace structure. The products of 90 combustion from the fire-box thus circulate up the first heating flue, down the second, up the third, and down the fourth and pass to the stack through stack flue 18. The heating units 20 of the first compartment of 95 the drum are contained in the first heating flue; the heating units 20^a of the second compartment in the second heating flue, and so on, so that there is a substantial drop in 100 temperature between each unit and the following unit due to the cooling of the gases from the fire-box. The temperature may also be regulated or adjusted in the successive flues by valves V and V' in the supplemental passages P and P'. 105

In the preferred construction shown a conduit 40 containing a venturi or blower leads from the bottom of the last heating flue 13^c and connects with the first heating flue 13 at a point 18 behind the bridge wall 19 by which construction any desired proportion of the cooled products of combustion may be returned to flue 13 and mixed with the fresh products of combustion rising 110 from the fire-box to modify the temperature thereof to prevent overheating of the first set of oil heating tubes. Furthermore, by the return of the cooled products of combustion the total volume or mass of products of combustion brought into contact per unit 115 of time with the oil heating units and the velocity thereof are increased, the total amount of heat extracted from the fuel augmented, and the heat absorption more evenly distributed among the several sets of 120 heating tubes.

The heating unit connected to each compartment of the drum, in this specific illustration of our invention, comprises three 125 disinct elements or circulation systems, by 130

which oil is withdrawn from the compartment and circulated through the corresponding heating flue of the furnace and back to the same compartment. Each of these elements comprises a short header 21 connected into the bottom of the still compartment and a long header 25. These headers are arranged immediately outside of one wall of the furnace, as seen in Figs. 2 and 3, the 10 headers 21 being connected into the bottom of the still. The headers 25, as shown in Figs. 1 and 2, are arranged intermediate of and below headers 21. In the form of the invention shown a group of tubes connect 15 each header 21 with the corresponding header 25, each group of tubes comprising pipes 22 connected into headers 21 and extending downwardly therefrom and across the flue, cross headers 23 arranged on the 20 side of the furnace structure opposite headers 21 and 25, and pipes 24 extending downwardly from the cross headers 23 to the headers 25. Preferably the walls of the furnace are cut away or recessed as at 80 25 and 81 to receive said headers. The headers are formed with opening 26, normally closed by screw plugs 26^a as shown in Fig. 3, in order to permit the insertion of a tool for cleaning the pipes 22 and 24. The three 30 headers 25 in each group are closed at their upper ends, as best seen in Fig. 3, and are connected at their lower ends to common manifolds 27, which communicate by pipes 28 with the outlets of pump 30. The inlets 35 of said pump are connected by pipes 32 to the same compartment of the drum to which the heating tubes and headers supplied by said pump are joined. It will now be understood that when the pump is in operation 40 it receives oil to be cracked through the pipes 32 from the corresponding compartment of the drum and forces it through the headers and heating tubes back to the same compartment of the drum.

45 A separate pump may be employed for effecting the circulation in each of the compartments. It is convenient, however, that the pumps be arranged in a common casing and driven by common means and the construction is so shown in the drawings. We have chosen for the purpose of illustration what we have found to be the pump best adapted for the purpose, to wit: a rotary pump of the double piston type sometimes 50 known as a Connersville pump. As indicated in the drawings, the series of pumps is driven by a suitable motor 33 and the casing is divided by partitions 34 into a series of independent chambers 35, 35^a, etc., each containing a pair of pistons 36. These 55 pumps are connected to their respective compartments 10, 10^a, etc., of the drum on the inlet side by pipes 32 and to the corresponding manifolds 27 by its pipe 28, the 60 pumps being independent except in so far as

they are enclosed in the same housing and operated by the same mechanism.

A T 36 is inserted in the connection 28^c between the last heating unit and the corresponding pump for the attachment of a 70 draw-off F for the tar. By a suitable valve or the like the release of tar may be regulated as required.

In the specific exemplification of the invention disclosed herein there are three heating elements connected to each compartment and located in each heating flue, and in order to equalize, as nearly as may be, the heat absorption in the respective compartments, the number of pipes in the successive series 75 is increased; thus there are four pipes in each series connected to the first compartment, eight in each series connected to the second and so on. It follows that though the temperature of the products of combustion 80 declines progressively from the first pass or heating flue to the last, the heat absorption and therefore the cracking effect is approximately equalized.

85 From the foregoing the operation of the still will be apparent. The drum is filled to the desired level, preferably through the inlet B and the overflow pipes 11, 11^a, etc. Preferably, the subsequent supply is continuously introduced through the reflux 90 tower, where it is preheated and assists in condensing and returning to the drum the insufficiently cracked hydrocarbons. The pumps, being set in operation, continuously 95 circulate the oil upwardly through the respective heating units, the circulation being assisted by convective effect due to heating. The oil in the first compartment and its 100 heating unit will first reach cracking temperature and the other compartments and heating units will reach cracking temperature in order. As cracking and vaporization takes place, oil is continuously supplied to the first compartment, preferably through the reflux tower and, in the preferred operation, tar is continuously drawn off through the manifold 27^c and outlet pipe 28^c connected to the last heating unit. A branch pipe, provided with a valve, may be connected to pipe 28^c for this purpose. The 105 pumps are continuously operating during the run to maintain a rapid circulation of the oil in the respective compartments and heating units. The vapors rising from the several compartments all flow into the reflux tower, from which those of sufficiently low 110 gravity pass by the vapor line to the condenser while the heavier vapors are condensed and returned with the fresh oil to the first compartment. Thus the reflux oil is subjected to retreatment under the most favorable conditions for cracking in respect both to the temperature and the absence of free carbon in the oils with which 115 it is mixed and the oil in the first compartment.

ment and heating unit, which is subjected to the highest temperature, is provided with a flux of light oil.

The continuous supply of fresh oil to the first compartment, combined with the vaporization throughout the several compartments and the withdrawal of tar from the heating unit connected to the last compartment, causes a continuous movement of the oil through the successive compartments, which is accompanied by a successive diminution in the content of crackable hydrocarbons and an increase in the amount of tar and free carbon in the successive compartments and heating units. In a still constructed according to this invention, the oil is exposed to the highest temperature during that phase in the cracking thereof in which it contains the least carbon and the largest amount of lighter and convertible hydrocarbons, and consequently there is no serious deposition of carbon where it would be most objectionable. As the carbon increases and the content of crackable hydrocarbons diminishes in the successive compartments and corresponding heating units, this is offset in the successive heating units by the successive reductions in temperature and increases in the heating surface exposed to the hot gases and on which the carbon may deposit.

Furthermore, in the construction shown and described, the temperature and heat absorption in the several heating units may be controlled as desired by means of the venturi, returning a proportion of the products of combustion, and the valves V, V', of which obviously any desired number may be employed, controlling direct communication between the heating flues. Thus, by turning a greater proportion of the products of combustion from the final heating flue to the first heating flue, the temperature of the gases to which the heating unit in the latter is exposed is lowered without, however, a corresponding diminution in the heat absorption because of the increased volume of gases circulating through and about the heating tubes. This effect is also received by the successive heating units though in less marked degree, the tendency being in the direction of equalizing the heating effect. A still further equalizing effect may be obtained by opening to a greater or less extent the valves V, V'.

55 We claim:

1. In an oil still, a drum, a series of partitions dividing the drum into successive compartments, there being openings in said partitions through which the compartments communicate, means for supplying oil to the compartment at one end of said drum, a furnace having a heating flue, a series of separate heating units corresponding to the successive compartments in the drum each being connected to one of the compartments

and extending into the heating flue, the heating unit connected to the compartment at the supply end of the drum being arranged in the heating flue nearest the furnace, and pumps connected to the respective compartments and heating units for circulating oil from the compartments through the heating units and back to the same compartment. 70

2. In an oil still, a drum, partitions in the drum dividing it into a series of communicating compartments, means for feeding oil into the first compartment in the series, a furnace having a heating flue, a series of heating units corresponding to the compartments in the drum each heating unit being connected to one of the compartments and being located in the heating flue, the heating unit connected to the feed compartment being arranged in the heating flue nearest the furnace, and a corresponding series of pumps for forcing oil from said compartments through the heating units and back to the same compartment. 80

3. In an oil still, a drum having a series of communicating compartments, means for feeding oil to the first of said compartments and exhausting tar from the last of said compartments whereby a continuous flow may be had through said compartments, 90 means for conducting away the vapors generated, a furnace having a heating flue, a corresponding series of separate heating units each being connected to one of said compartments only and extending into the heating flue of the furnace, and a corresponding series of pumps connected to the compartments and to the heating units connected thereto and adapted to receive oil from said compartments and force it through the heating units and back to the same compartment. 95

4. In an oil still, a drum, a series of communicating compartments in the drum, means for feeding oil into the first of said compartments and exhausting tar from the last of said compartments, and means for leading away vapors from said compartments, a corresponding series of separate heating units connected to each of said compartments, a pump connected to each of said compartments and to the heating units connected thereto to cause the oil to circulate from the compartments through said heating units and back to the same compartment, and means common to the pumps to drive same. 110

5. In an oil still, a drum, partitions in the drum dividing same into a series of communicating compartments, means for feeding oil into the first of said compartments, means for withdrawing tar from the last of said compartments, a furnace, a corresponding series of separate heating units connected to the respective compartments and

- located in the furnace, each of said heating units comprising a header connected to the drum, a series of pipes connected to the header and a second header, a series of rotary pumps having rotary pistons, the pistons of the respective pumps being mounted on common shafts, means for driving said shafts, connections from the inlets of the respective pumps to the respective compartments of the drums, and connections from the respective outlets of the pumps to the respective second said headers of the heating units.
6. In an oil still, a drum, transverse partitions in the same dividing the lower portion thereof into successive communicating compartments, means for feeding oil into the first of said compartments at one end of the drum, means for withdrawing residue at the far end of the drum, means for leading away vapors, a furnace having a fire box adjacent the first mentioned end of the drum, an outlet flue adjacent the drawoff end of the drum, flues connecting the firebox and outlet flue, heating units communicating with the respective compartments and extending into the heating flue, and pumps connected on the outlet side to each said heating unit and on the inlet side to the corresponding compartment of the drum.
7. In an oil still, a drum, transverse partitions in the drum dividing the lower portion thereof into successive communicating compartments, means for supplying oil to the compartment at one end of the drum, means for permitting the escape of residues from the compartment at the opposite end of the drum, a line for leading off vapors, a furnace having a heating flue extending along the drum, a firebox communicating with the end of the flue beneath the first mentioned end of the drum, and a stack flue at the other end of the heating flue, heating units for each compartment each comprising headers communicating therewith, pipes connected to the headers at one end, headers to which the pipes are connected at their other ends, a manifold to which the last named headers of each unit are connected, a pump the outlet side of which is connected to said manifold and a connection from the inlet side of the pump to the corresponding compartment.
8. In an oil still, a drum, transverse partitions in the drum dividing the lower part thereof into successive communicating compartments, means for feeding oil into the first of said compartments at one end of the drum, means for withdrawing residue from the last of said compartments at the other end of the drum, a vapor line, a furnace comprising heating flues extending beneath the drum, a fire box for said furnace at the end of the heating flues corresponding to the first compartment of the drum, an outlet flue connected to the exhaust end of the heating flues, independent heating units communicating with the respective compartments, the heating areas of which increase progressively from the first to the last unit, pumps connected on their outlet sides to the respective heating units, and pipes connecting the inlets of the respective pumps to the corresponding compartments of the drum.
9. In an oil still, a furnace having a heating flue, a drum adapted to contain a charge of oil, heating means arranged in the heating flue and connections including a pump for circulating oil from and to the drum therethrough, a separate heating means communicating with the drum arranged in the heating flue between the first mentioned heating means and the furnace, connections for supplying fresh oil to the still and means for initially circulating the fresh oil through the last mentioned separate heating means.
10. In an oil still, a furnace having a heating flue, a drum adapted to contain a charge of oil, heating means arranged in the heating flue and connections including a pump for circulating oil from and to the drum therethrough, a separate heating means communicating with the drum arranged in the heating flue between the first mentioned heating means and the furnace, connections for supplying fresh oil to the still and means including a pump for initially circulating the fresh oil through the last mentioned separate heating means.
11. In an oil still, a furnace having a heating flue, a drum adapted to contain a charge of oil, a reflux tower communicating with the drum, heating means arranged in the heating flue and connections including a pump for circulating oil from and to the drum therethrough, a separate heating means communicating with the drum arranged in the heating flue between the first mentioned heating means and the furnace, connections for supplying fresh oil to the still and connections for returning reflux from the reflux tower to the still, and means for initially circulating the fresh oil and reflux through the last mentioned separate heating means.
12. In an oil still, a furnace having a heating flue, a drum adapted to contain a charge of oil, a reflux tower communicating with the drum, means for introducing fresh oil into the reflux tower, heating means arranged in the heating flue and connections including a pump for circulating oil from and to the drum therethrough, a separate heating means communicating with the drum arranged in the heating flue between the first mentioned heating means and the furnace, and means for initially circulating the fresh oil and admixed reflux from the

reflux tower through the last mentioned separate heating means.

13. In an oil still, a furnace having a heating flue, a drum adapted to contain a charge of oil, a reflux tower communicating with the drum, heating means arranged in the heating flue and connections including a pump for circulating oil from and to the drum therethrough, a separate heating

means communicating with the drum arranged in the heating flue between the first mentioned heating means and the furnace, and means for initially circulating the reflux from the reflux tower through the last mentioned separate heating means. 10
